UNITED STATES PATENT OFFICE.

ROBERT J. PAUL, OF GILMAN, IOWA.

EVENER.

1,109,868.

Specification of Letters Patent.

Patented Sept. 8, 1914.

Application filed January 31, 1914. Serial No. 815,795.

To all whom it may concern:

Be it known that I, ROBERT J. PAUL, a citizen of the United States, residing at Gilman, in the county of Marshall and State 5 of Iowa, have invented a certain new and useful Evener, of which the following is a specification.

The object of my invention is to provide a five-horse evener especially designed as a 10 long draw bar for a multiple section harrow.

It is especially my object to provide a draw bar evener of simple, durable and inexpensive construction so constructed that points of attachment may be provided close 15 to the draw bar for the eveners for three-horse and two-horse teams respectively, and also so constructed as to give each of the eveners separate points of connection with the draw whereby a too great swinging 20 movement of the draw bar with relation to the eveners is prevented.

My invention consists in certain details, in the construction, arrangement and combination of the various parts of the device, 25 whereby the objects contemplated are attained, as hereinafter more fully set forth, pointed out in my claims, and illustrated in the accompanying drawings, in which the figure represents a plan view of my evener 30 for harrows with a plurality of harrow sections attached thereto and with three-horse and two-horse eveners secured to the draw bar of the evener.

In the accompanying drawings, I have 35 used the reference numeral 10 to indicate generally a draw bar which may be made of any suitable material. Harrow sections 12 may be secured to the draw bar 10 by means of the links 11.

40 For hitching a five-horse team to the draw bar 10 for driving the harrow sections, the following parts are provided: At the center of the harrow is a forwardly extending arm 13 in which is mounted a roller 14, shown by the dotted lines in the figure.

For the sake of illustration, I shall give 45 definite lengths but it will be understood that the lengths may be varied proportionately if desired. Pivoted to the bar about fifteen inches on one side of the arm 13 is a forwardly extending arm 15. At the same distance from the arm 15, on the side opposite the arm 13, is fixed a forwardly extending arm 16 in which is mounted a roller 17 shown by the dotted lines.

Pivoted to the bar 10, about five feet

from the arm 16 and between said arm and the nearest end of the bar 10 is a link 18. Pivoted to the bar 10 between the arm 13 and the other end of the said bar, and about seven and one half feet from the arm 13 is 60 a similar link 20. Secured to the links 18 and 20 are rings 19. Secured to the ring 19 of the link 18 is a chain 21 which is extended around the roller 17 and is secured to the outer forward end of the arm 15. Secured to the ring 19 of the link 20 is a chain 22 extended around the roller 14 and secured to the arm 15 at such a point that the distance between where the chain 22 is secured 65 to the arm 15 and the pivotal point of said arm is one half greater than the distance between where the chains 22 and 21 are secured to said arm 15. For example, the distance from A to B is three fifths of a 70 foot and the distance from A to C is two fifths of a foot.

There is secured an ordinary three-horse evener 23 to the ring 19 on the link 20 and an ordinary two-horse evener 24 to the ring 80 19 on the link 18. It will be seen that the draft is then properly equalized for permitting the two horses to draw two fifths of a load and the three horses to draw three fifths thereof.

It may be noted that the links 18 and 20 might be flexible devices if desired and that the link 20 is somewhat longer than the link 18 for the simple reason that the rings 19 are designed in operation to be substantially midway between the pivotal points of the links and the nearest adjacent forwardly extending arms 13 and 16 respectively.

My improved evener is designed especially 95 for harrows and has the advantage of securing the eveners 24 and 23 to different points on the draw bar and also for securing them close to the draw bar and at the same time equalizing the draft properly.

One of the difficulties in dragging a harrow is that with ordinary eveners, the horses are too far from the harrow and on making turns, or one end of the harrow strikes an obstruction, the harrow sags and swings 105 widely.

On account of the fact that the links 18 and 20 are secured well toward the ends of the bar 10, and the further fact that the eveners 24 and 23 are close to the bar, my 110 bar 10 does not greatly sag or swing away from, or toward the horses at any time.

I claim as my invention:

1. In a device of the class described, an evener bar designed to be attached to a plurality of harrow sections, a forwardly extending arm at the center thereof, links pivoted to said evener bar at points spaced apart from the center thereof, a forwardly extending arm pivoted to said bar spaced apart from said first arm at a distance equal to one sixth of the distance between said arm and one of said links, a second forwardly extending arm secured to the bar at a similar distance from said pivoted arm on the side nearest the adjacent link, flexible devices secured to the links slidably extended through the nearest respective fixed forwardly extending arms and secured to said pivoted arm at points distant from the pivotal point of said arm in the proportion of three and five.
2. In a device of the class described, a bar, means for securing harrow sections thereto, a forwardly extending arm pivoted thereto at one side of the center thereof, draft devices secured thereto at points equidistant from the ends thereof, and longer and shorter flexible draft devices secured to the respective first devices on the long and short ends of the bar, said flexible devices being slidably mounted on said bar at points on each side of said arm and equidistant therefrom, and secured to said arm at such points that the distance from the point where the shorter flexible device is attached to the bar, from the point where the longer flexible device is secured to the bar, bears the same relation to the distance of the latter point from the pivotal point of the bar that the burden of draft, designed to be drawn from

the shorter flexible draft device, bears to the burden of draft, designed to be drawn to the longer flexible device.

3. In a device of the class described, a bar, means for securing harrow sections thereto, a forwardly extending arm pivoted thereto at one side of the center thereof, draft devices secured thereto at points equidistant from the ends thereof, and longer and shorter flexible draft devices secured to the respective first devices on the long and short ends of the bar, said flexible devices being slidably mounted on said bar at points on each side of said arm and equidistant therefrom, one of said points being at the middle of the bar, and secured to said arm at such points that the distance from the point where the shorter flexible device is attached to the bar, from the point where the longer flexible device is secured to the bar, bears the same relation to the distance of the latter point from the pivotal point of the bar that the burden of draft, designed to be drawn to the longer flexible device, bears to the burden of draft designed to be drawn to the shorter flexible device, said parts being arranged so that the flexible devices may be detached from said arm and said bar except at the center of the latter, so that draft bars for even draft hitch may be secured to the flexible devices at points equidistant from the center of the bar.

Des Moines, Iowa, January 10, 1914.

ROBERT J. PAUL.
